UNITED STATES PATENT OFFICE.

RAYMOND STARNER PECK, OF VICKSBURG, MISSISSIPPI.

AIR-REGULATING FIRE SHIELD.

Application filed June 2, 1927. Serial No. 196,086.

This invention relates to shields for application to the fire box doorway of a locomotive boiler furnace and is an improvement of the subject matter disclosed in my co-pending application, Serial Number 113,736, filed June 4, 1926.

An object of the present invention is to provide an improved type of shield capable of being utilized to regulate the quantity of air permitted to pass through the upper portion of the doorway while the shield is in operative position.

Other purposes, advantages and characteristic features of the invention will be more readily understood from the following detailed description and accompanying drawings, in which,

Figure 1 is a fragmentary front elevational view of a fire box equipped with the improved shield.

Figure 2 is an edge view of the shield as it will appear when adjusted to admit a relatively small volume of air through the upper portion of the fire box doorway.

Figure 3 is an edge view of the shield as it will appear when it is adjusted to admit the maximum volume of air capable of being passed through the upper portion of the doorway while the shield is in operative position and,

Figure 4 is an edge view of the shield as it will appear when it is secured in an inoperative position to give access to substantially the total area of the doorway.

Proceeding now to a more detailed discussion of the drawings 11 designates a shield normally overlying the upper portion of the fire box doorway 12 and hinged at 13 to a supporting strip 14. This strip is suspended by a bracket 15 from the door guide 16 of the furnace structure.

As indicated by dotted lines in Figure 1, shield 11 is apertured to provide a plurality of air passages 17 normally closed by a flap 18. This flap is hinged, at 19, to the strip 14 and tends to lie flat against the outer surface of the shield. The central upper edge portion of the flap is slotted at 20 to permit the flap to be swung upwardly without interference by the bracket 16. An adjusting screw 21 is threaded through the flap 18 to bear against the outer surface of the shield 11 so that by turning this screw the flap may be adjusted to or from the shield to thereby control the quantity of air admitted between the shield and flap for de-

livery to the fire box through the passages 17. When it is desired to pass a large volume of air into the fire box through the passages 17 the flap 18 is swung upwardly 60 and secured in the position shown in Figure 3 by engaging the hook 22 or the flap in an eye 23 carried by the slide bar 15.

When the shield is to be displaced to an inoperative position to give free access to the upper portion of the fire box for repair or other purposes it is secured to the flap by means of the hook 24 carried by the flap and engageable in the eye 25 of the shield and the shield and flap are then both swung 70 upwardly to the position shown in Figure 4 and retained in such position by engagement of the hook 22 with the eye 23.

The shield 11 and flap 18 are normally suspended as shown in Figure 1 with the flap lying against the outer surface of the shield and closing the air passages 17. In this position of the parts there is little or no air admitted into the fire box through the upper portion of the doorway 12. When 80 the flap is swung outwardly by the operation of screw 21 the air admitted beneath the flap for delivery into the fire box through the passages 17 is caused to be distributed evenly over the bed of the fire by the arrangement of said passages. By regulating, through the medium of screw 21, the clearance provided between the flap 18 and the underlying shield 11 the quantity of air delivered through the passages 17 may be 90 regulated between minimum and maximum limits so as to insure efficient combustion for varying conditions of engine operation. When the maximum quantity of air is to be delivered into the fire box through the 95 passages 17 the flap 18 is secured in the position shown in Figure 3 as previously explained.

Besides controlling the quantity of air admitted into the fire box through the upper 100 portion of the doorway 12 it will be understood that the shield structure herein disclosed serves to protect the fireman from the intense heat within the fire box without interfering with the delivery of fuel into 105 the fire box through the lower portion of the doorway 12. As shown to advantage in Figure 1 the shield 11 is spaced a sufficient distance from the furnace structure to permit the doors 26 of the fire box to operate 110 therebetween and the doorway 12. It is thus apparent that the shield structure is

itself subjected to the intense heat within the fire box only in the open position of the doors and is protected by the latter when moved to closed position.

5 Having thus fully described what I now conceive to be the preferred embodiment of the invention it will be understood that various changes in the construction, arrangement and combination of parts may be resorted 10 to within the scope and spirit of the invention as defined by the appended claims.

What I claim is:

15 1. A shield of the character described provided with air passages and means for controlling the quantity of air delivered therethrough.

20 2. A shield of the character described comprising an apertured plate and an aperture closing flap hingedly connected thereto.

25 3. A shield of the character described comprising a member adapted to be secured at the upper edge of a furnace doorway, an apertured plate hinged to said member to overlie the upper portion of the doorway and means for controlling admission of air through the apertured portion of the plate.

30 4. A shield of the character described comprising an apertured plate adapted to overlie the upper portion of a furnace doorway, a flap normally closing the apertured portion of the plate and means for adjusting the flap to regulate admission of air through the said apertured portion of the plate.

35 5. A shield of the character described

comprising an apertured plate provided with means for hingedly suspending the same from a furnace structure to overlie the upper portion of the fire box doorway, a flap hingedly connected to the shield and normally serving to close the apertured portion of the plate, means for adjusting the flap relatively to the plate to regulate the quantity of air admitted into the fire box through the apertured portion of the plate, and means for securing said flap in raised position to freely expose the apertured portion of the plate when a maximum amount of air is to be admitted through said apertured portion of the plate for delivery to the fire box.

40 6. A shield of the character described comprising a plate having apertures formed therein, a strip hingedly connected to one edge of said plate, a flap hingedly connected to said strip and adapted to normally lie against one face of the plate and to close the apertures therein, means for securing said strip to a furnace structure to dispose the apertured plate over the upper portion of the fire box doorway, means for detachably securing the apertured plate to the said flap and means carried by the flap and engageable with complementary means carried by the furnace to secure the flap in an upwardly swung position with reference to the fire box doorway.

45 In testimony whereof I hereunto affix my signature.

RAYMOND STARNER PECK.
